UNITED STATES PATENT OFFICE.

WILLIAM C. CODMAN, OF PROVIDENCE, RHODE ISLAND, ASSIGNOR TO
GORHAM MANUFACTURING COMPANY, OF PROVIDENCE, RHODE
ISLAND.

DESIGN FOR A HANDLE FOR SPOONS, FORKS, OR SIMILAR ARTICLES.

SPECIFICATION forming part of Design No. 37,239, dated November 22, 1904.

Application filed October 26, 1904. Serial No. 230,144. Term of patent 14 years.

To all whom it may concern:

Be it known that I, WILLIAM C. CODMAN, a subject of the King of Great Britain, residing at Providence, in the county of Providence and 5 State of Rhode Island, have invented a new, original, and ornamental Design for the Handle of a Fork, Spoon, or Similar Article, reference being had to the accompanying drawing.

10 The figure in the drawing is an obverse

view of my design for the handle of a fork, spoon, or similar article.

What I claim as new, and desire to secure by Letters Patent, is—

15 The ornamental design for the handle of a fork, spoon or similar article, as shown.

WILLIAM C. CODMAN.
